(57) **CLAIM**

The ornamental design for automobile headlamp lighting signature, as shown and described.

DESCRIPTION

FIG. 1 is a front elevation view of an automobile headlamp lighting signature showing our new design;
 FIG. 2 is a front and left perspective view thereof; and,
 FIG. 3 is a left side elevation view thereof.

(Continued)

The portions of the automobile headlamp shown with diagonally-hatched lines are provided for the purposes of illustrating environmental structure and forms no part of the claimed design.
